US0D1062720S

(12) **United States Design Patent** (10) **Patent No.:** **US D1,062,720 S**
(45) **Date of Patent:** **** Feb. 18, 2025**

(54) **COMPUTER HOST**

(71) Applicant: **Acer Incorporated**, New Taipei (TW)

(72) Inventors: **Ming-Cheng Wu**, New Taipei (TW);
Yi-Heng Lee, New Taipei (TW)

(73) Assignee: **Acer Incorporated**, New Taipei (TW)

(**) Term: **15 Years**

(21) Appl. No.: **29/730,855**

(22) Filed: **Apr. 9, 2020**

(51) LOC (15) Cl. **14-02**

(52) U.S. Cl.

USPC **D14/314**

(57) **CLAIM**

The ornamental design for a computer host as shown and described.

DESCRIPTION

FIG. 1 is a perspective view of a computer host showing our new design;

FIG. 2 is another perspective view thereof;

FIG. 3 is still another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines illustrate portions of the computer host that form no part of the claimed design.

1 Claim, 9 Drawing Sheets
